Term of patent 14 years

(Cl. D44—1)

FIG. 1

FIG. 3

FIG. 2

FIG. 4

FIG. 6

FIG. 5

FIGURE 1 is a perspective view of a food mold or the like showing my new design;

FIGURE 2 is an exploded perspective view thereof;

FIGURE 3 is a side elevational view;

FIGURE 4 is a perspective view of another form of the food mold or the like showing my new design;

FIGURE 5 is an exploded perspective view thereof; and

FIGURE 6 is a transverse sectional view thereof.

The essential portions of my design are shown in the full lines of the drawings.

This is a continuation-in-part of my earlier filed application Serial No. D. 82,237, filed October 20, 1964, and entitled "Mold for Congealable Comestibles" and now abandoned.

I claim:

The ornamental design for a food mold or the like, substantially as shown and described.
